HOSIERY INSPECTING DEVICE

Samuel Edward Kalbach, Wyomissing, and Max Poeschmann, West Reading, Pa., assignors to Textile Machine Works, Wyomissing, Pa., a corporation of Pennsylvania

Application August 26, 1933, Serial No. 686,968

48 Claims. (Cl. 223—77)

This invention relates to a device for inspecting hosiery, particularly hosiery of the full fashioned flat knit type, wherein the stockings are shaped or fashioned by laterally transferring 5 stitches adjacent the opposite edges of the blank during the formation of predetermined stitch courses, after which the blank is folded longitudinally and the opposite edges thereof joined together in a seam extending from the tip of the 10 toe, under the sole of the foot and heel, and up the back of the leg to the top edge of the welt of the stocking.

The transferring of the stitches in the fashioning of the stocking is automatically performed by 15 transfer points which are adapted to be aligned with and to engage predetermined needles, lift the stitches from the needles and then move laterally into alignment and engagement with adjacently disposed needles, onto which the lifted 20 stitches are transferred by relative movement between the points and the needles.

Due to improper alignment between the needles and the points, usually caused by bending of one or the other of these rather delicate elements, 25 there are times when one or more of the stitches are not properly transferred onto the needles adapted to receive them or during the lifting of the stitches from the needles by the transfer points it may happen that the point will split the 30 thread. Likewise in seaming the stocking blank it is possible that the needle or looping element may split the thread of some of the stitches adjacent the edges of the blank.

In many cases the above noted defects do not 35 become apparent during the finishing of the stocking and not until the stocking is being "put on" by the ultimate consumer, when, by reason of the stocking being subjected simultaneously to transverse and longitudinal strain, as the stocking 40 is being pulled on and over the foot and up the leg of the wearer, the dropped or imperfect stitches produced by the improper transferring and/or the split thread in one or more of the 45 stitches will give way and start a runner or ladder in the stocking.

Some of the objects of the present invention 50 are, to provide a novel device for inspecting the stocking after the seaming of the blanks, whereby the stocking will be subjected to radial expansion, strains and longitudinal tension assimilating the stresses to which the stocking is subjected 55 during its application to the limb of the wearer; to provide such a device which can also be operated to produce a lateral stress extending from

the round of the heel across the instep, whereby the stocking fabric around the turning points of the heel tabs is placed under maximum strain; to provide a device of this kind with interchangeable parts so that it may be adapted for inspecting hosiery of different characteristics with equal facility; and to provide such a device which is highly efficient and can be quickly and easily operated.

With these and other objects in view, which 10 will become apparent from the following detailed description of several illustrative embodiments of the invention shown in the accompanying drawings, the invention resides in the novel elements, features of construction and arrangement of parts 15 in cooperative relationship as hereinafter more particularly pointed out in the claims.

In the accompanying drawings:

showing certain parts of the mechanism disconnected;

Fig. 17 is a sectional plan view taken on the line 17—17, Fig. 15;

Fig. 18 is a detail plan view showing certain elements of the device in relatively different positions from those illustrated in Fig. 17;

Fig. 19 is a transverse sectional elevation taken on the line 19—19, Fig. 17;

Fig. 20 is a sectional elevation of a detail taken on the line 20—20, Fig. 15;

Fig. 21 is a sectional elevation similar to Fig. 15, showing a modification of the invention;

Fig. 22 is a sectional elevation taken on the line 22—22, Fig. 21;

Fig. 23 is a view similar to Fig. 22, but showing certain of the elements in different positions;

Fig. 24 is a sectional elevation taken on the line 24—24, Fig. 21, certain parts being shown in full 20 and others broken away to more clearly disclose the construction.

Fig. 25 is a view similar to Fig. 24 showing certain elements in different positions; and

Fig. 26 is a modification of the invention illustrating a readily removable and interchangeable tip for the stocking form.

As shown in Figs. 2, 13 and 17, the device comprises a main head 1 which is adapted to be secured firmly to a suitable rigid support in any 30 of a plurality of possible positions, as will be fully disclosed hereinafter.

Projecting laterally from one side of and rigidly secured in the head 1 is a relatively short fixed stud or post 2 which, in the present instance, 35 carries ball-bearings 3 and 4 disposed in one end of and adapted to rotatably support a relatively long hollow center post 5, which is axially aligned with and adapted to rotate freely about the axis of the short post or stud 2 concentrically there- 40 with.

The form on which the stockings S are placed for inspection, in the present case, is of a fully closed type presenting a fabric engaging and supporting surface to practically all portions of the 45 area of the stocking fabric, said form consisting of an expansible shell 6 disposed outside and surrounding the central rotary post 5, and extending substantially from the head 1 to a position beyond the outermost end of the central 50 post 5. The shell 6, in its contracted state, as shown in Figs. 13 and 14, is of a substantially circular cross-sectional contour and tapers gradually from its larger end, adjacent the head 1, to a relatively small diameter beyond the outer end 55 of the central post 5.

The shell 6 is composed of a plurality of longitudinally extending radially movable segments, in the present instance consisting of two similar 60 halves of the form designated as 6a and 6b, respectively.

Axially aligned with the tapering leg portion of the expansible shell 6 and extending beyond the outer end 7 thereof is a substantially cylindrical foot portion 8, composed of two similar 65 halves 8a and 8b respectively secured to the halves 6a and 6b of the leg portion 6 of the expansible shell form, for relative expansion and contraction with the segmental sections 6a and 6b of the form respectively.

The foot portion 8 of the form is adjustable axially with respect to the leg portion 6 thereof, whereby the inner end 9 of the foot portion 8 is adapted to be moved away from the outer end 75 7 of the leg portion 6 for the reception of filler

pieces 10, 10 between the corresponding halves of the tapering leg shell 6 and the cylindrical foot piece 8 respectively.

The longitudinally extending segmental sections 6a and 6b of the shell 6 are supported adjacent one end of the shell 6 by the central post 5 for radial expansion and contraction with respect to the longitudinal axis thereof, by means of a pair of inwardly extending plate-like lugs 11a and 11b which are respectively secured to or formed integral with the segmental elements 6a and 6b of the shell 6, said lugs 11a and 11b being disposed in overlapping and interlocking slidable relation to each other and slidably mounted in longitudinally and transversely extending slots 12, 12 formed respectively in the opposite sides of the hollow central post 5.

The segmental sections 6a and 6b are further supported adjacent the opposite end of the shell 6 by and for radial movement with respect to the central post 5 by transversely extending rods 13a and 13b pivoted at their outer ends to the shell segments 6a and 6b respectively, as indicated at 14, 14. Each of the rods 13a and 13b is slidably mounted in a transversely extending bearing 15 carried by or formed in the central post 5.

Lateral or radial expansion and contraction of the segmental sections of the form, each consisting of one of the halves of the leg shell 6 with one of the halves of the foot piece 8 secured thereto, is effected by means of a centrally disposed longitudinally reciprocable operating element 20, which is mounted within the central hollow post 5, in axial alignment with the fixed post 2, said operating element 20 being provided with an axially aligned cylindrical rod-like end 19 which is supported by, slidably mounted in, and extends completely through the relatively short fixed post or stud 2 and adapted for reciprocation axially of and within said fixed post 2.

As shown in Figs. 5 and 13, the opposite or outer end of the operating element 20 is also of a cylindrical or rod-like form similar to the end 19 thereof as indicated at 19a, said latter end being 45 slidably mounted in and supported by a bearing 2a formed in or carried by the outer end of the central post 5.

The operating element 20 intermediate the ends 19, 19a thereof is provided with relatively enlarged portions 17 and 18 respectively, in which are formed longitudinally extending slots 17a and 18a respectively.

The overlapping and interlocking relatively slidable supporting lugs 11a and 11b of the shell 55 halves 6a and 6b, respectively, project into the slot 17a from opposite sides thereof and are provided with oblique slots 21a and 21b, respectively, through which extends an operating pin 22. The opposite ends of the pin 22, which extend above 60 and below the plates or lugs 11a or 11b, are rigidly secured in the upper and lower walls of the enlargement 17 of the operating element 20, whereby longitudinal movement of the operating element 20 will cause the pin 22 to move longitudinally within the oblique slots 21a and 21b, and which, due to the slots extending at opposite angles to each other, as shown in Fig. 2, 65 relative lateral movement between the shell sections 6a and 6b in opposite directions with respect to each other and radially with respect to the axis of the central post 5 is effected.

The transversely extending supporting rods 13a and 13b are provided with pins 24 and 25 respectively, which extend at right angles to the 75

axes of the rods 13a and 13b and project through slots 26, 26 formed in the bearings 15, 15 respectively, with the projecting ends of said pins disposed in slots 27a and 27b formed in the upper 5 and lower walls of the enlargement 18 of the operating element 20, said oblique slots 27a and 27b extending in opposite angular directions to each other whereby longitudinal movement of the operating element 20 will cause the slots 27a 10 and 27b through the pins 24 and 25 riding therein to move the rods 13a and 13b radially and in opposite directions with respect to the central post 5, whereby a movement of each of the segments 6a, 6b at the larger end of the tapered 15 shell 6 corresponding to the movement of said segments at the smaller end of said shell, or a differential movement by the ends of the segments at the larger end of the shell 6 in excess of the movement of the segments at the smaller 20 end of the shell 6, is effected, said differential movement between the opposite ends of the expandable shell 6 being provided to take care of the larger diameter of the welt and immediately adjacent section of the leg of the stocking relative 25 to the smaller diameter ankle and lower calf portions of the stocking.

By expanding the shell 6 radially, in the manner noted, the whole of the leg portion of the stocking is simultaneously placed under tension 30 corresponding to that to which the leg portion of the stocking is subjected when being placed on the limb of the wearer, practically all portions of the stocking fabric being equally stretched at the same time by contact with the surface of the shell, and whereby a slight relative rubbing of 35 the stocking over the surface of the shell is provided by the concurrent radial expansion of the fabric engaging segmental surfaces of the form corresponding to the rubbing action of the stocking 40 ing over the skin of the wearer's limb. As the leg shell 6 is expanded the foot cylinder 8 is correspondingly expanded and the fabric of the foot of the stocking is subjected to the same radial stress and relative rubbing action as in applying 45 the stocking foot to the foot of the wearer. At the same time, the operator making the inspection draws the stocking longitudinally of the expandable form producing therein practically the same longitudinal tension to which the stocking 50 is subjected in being drawn up onto the leg of the wearer.

The longitudinal and transverse tension produced in the heel and instep portions of the stocking by drawing the stocking over the heel 55 and instep of the foot is assimilated in the expandable form of the present invention by the provision of a radially movable heel expander illustrated at 30 in Figs. 1, 5 and 13.

In the present instance the heel piece 30 is pivoted at 31 to a lug 40 formed on and at the extreme outer end of the central post 5. The heel piece 30 is adapted to be swung from the collapsed position illustrated in Fig. 13 to the projected positions illustrated in Figs. 1 to 5, 60 through a slot 46 formed half in one of the shell segments 6a and half in the other shell segment 6b of the shell 6.

The radial projecting or extending movement of the heel expander 30 is effected simultaneously 65 with the radial expansion of the segmental sections of the form each including a leg portion and foot portion thereof, by a pin 32 projecting laterally from each side of an enlargement 33 formed on or carried by the extreme outer end 70 of the cylindrical section 19a of the operating ele-

ment 20, which extends into slots 34, 34 formed in plates or ribs 35, 35 respectively carried by or formed on the heel expander 30 adjacent the pivot 31 thereof.

As shown in Fig. 5, the pivot for the heel expander 30 is formed in the side plates 35, 35 and the main or body portion 36 of said expander is adjustable with respect to the plates 35 and to the pivot 31, whereby the degree of tension to be applied to the stocking by the heel expander 30 may be readily controlled.

As shown in Figs. 5 and 6, the body portion 36 of the heel expander 30 is provided with a central rib 37 against the opposite side of which the plates 35, 35 are secured and clamped by means of screws 38 passing through one of the plates 35 and slots 39, 39 formed in the central rib 37 and threaded into tapped openings formed in the second of the plates 35. Loosening of the screws 38, 38 will permit of relative movement 20 being effected between the body 36 and the plates 35 and between the body 36 and the pivot 31 for controlling the tension applied to the stocking by the heel expander 30.

As noted above, the foot portion 8 is adjustable longitudinally with respect to the leg portion 6 of the expandable form, and as shown in Figs. 2 and 10 the halves 8a and 8b of the foot piece 8 are respectively provided with tongues 41, 41 which are slidably mounted in grooves 45, 45 formed in the outer ends of the shell halves 6a or 6b respectively, said tongues 41 having a dovetailed sliding fit connection with the two halves of the shell 6, as clearly illustrated in Figs. 6, 11 and 12.

As shown in Fig. 11, the halves 8a and 8b of the foot piece 8 are secured in their adjusted positions with respect to the shell halves 6a and 6b, to which the said foot pieces are respectively attached, by means of locking screws 42, 42, 40 each provided with an annular flange 43, one side of which extends into a longitudinal groove 44 formed in the correlated tongue 41, whereby after each axial adjustment of the foot parts with respect to the leg parts of the expandable form, 45 tightening of the screws 42 will lock the tongue 41 firmly in the dovetail grooves 45 in which said tongues are respectively mounted.

As shown in Figs. 2 and 17, the rod end 19 of the operating element 20, at the opposite side 50 of the head to that from which the central post 5 projects, is provided with a piston-like head 50 which is slidably mounted in a cylinder 51 formed within a casing 52 which is secured to the head 1 against relative circular and longitudinal movement with respect thereto. Ball-bearings 53 and 54 are provided between the piston 50 and the extreme end of the rod 19, providing for relative circular movement between the rod 19 and piston 50 while preventing relative longitudinal movement between the two.

The post 2 is counterbored, as illustrated at 55 in Fig. 17, to receive and form an abutment for one end of a rod-encircling spring 55a, the opposite end of which is seated in a cup 56 which in turn is seated against one end of the piston head 50, tending at all times to move the rod 19 and consequently the operating element 20 in a direction to effect collapsing of the expandable stocking inspecting form.

Movement of the rod 19 and the operating element 20 in the opposite direction, to effect expansion of the form, is produced by a gear segment 57 pivotally mounted at 58 to the casing 52, the teeth of said gear segment intermeshing 75

with the teeth of a gear rack 59 secured to the piston 50 and projecting through a longitudinally extending slot formed in one side of the cylinder 51, whereby rocking of the segment 57 about its pivot 58 in one direction will move the piston 50 in a corresponding direction in the cylinder 51, thereby effecting similar movement of the rod 19 and operating element 20 in opposition to the spring 55.

Movement of the operating element 20 in the last said direction is limited by a split collar 60 threaded onto an axial extension 61 of the piston 50 operating in a supplementary cylinder 51a formed at the one end of the cylinder 51, said collar being adapted to engage the end wall 62 of the cylinder 51 and thereby limit the movement of the operating element 20 in the form expanding direction, whereby the extent of the expansion of the collapsible stocking form is definitely determined and excessive stretching of the stocking on the form prevented.

The limiting collar 60 is adapted to be locked in its adjusted position by a screw 63 extending parallel to the axis of the extension 61 across the split 64 in the collar to draw the two portions of the collar together and thereby firmly clamp the collar to the piston extension 61.

Pivots connected at 65 to a crank boss on the segment 57 is one end of a link 66, the opposite end of which is pivotally connected, at right angles to the pivot 65, as indicated at 67, to one end of a link 68. The opposite end of the link 68 is universally connected at 69 (see Fig. 20) to a pivot stud 70, which is adjustably mounted in a slot 71 extending longitudinally of a lever 72, the hub 73 of which is rotatably mounted on a shaft 74. The shaft 74, in the present instance, is rotatably mounted in bearings 75 and 76 secured to the underside of a table 77.

In the present instance the main head 1 of the stocking inspecting form is provided with a depending neck 78 on the lower end of which is formed a ball head 79. The ball head 79 of the main head 1 is universally adjustable in and adapted to be clamped rigidly by a split bearing 80 formed on the outer end of a bracket 81 which is secured to the underside of a table 77, the ball head 79 and bearing 80 providing for universal adjustment of the collapsible stocking form at any desired angle relative to the table, vertically and/or horizontally. The universal linkage between the operating segment 57 and the operating shaft 74 provides for operation of the operating element 20 from the shaft 74 regardless of the angle of the collapsible stocking form relative to the table.

As shown in Fig. 20, the operating shaft 74 is circumferentially grooved at 81 for the reception of one end of a screw 82 carried by the hub 73 of the lever 72, which fits within the groove 81 and which, while permitting relative rotation between the shaft 74 and the hub 73, prevents longitudinal movement of one with respect to the other.

Formed on and extending from the hub 73 is a second lever 83 which is connected by a link 84 to the outer end of a piston rod 85. The inner end of the piston rod 85 is connected to a piston 86 reciprocably mounted in a cylinder 87 which is secured to the underside of the table 77.

Secured to the shaft 74 is a lever 88 which is connected by a link 89 to a slide valve 90 by which motivating fluid, such as steam or compressed air, is admitted to and exhausted from the opposite ends of the cylinder 87 to effect reciprocation of the piston 86 therein, by which expansion and contraction of the collapsible stocking form is effected.

Secured to the shaft 74 is a pair of depending arms 91, 91, on and between the lower ends of which is mounted a foot treadle 92, whereby rocking of the shaft 74 to effect operation of the valve 90 is effected.

The rocking motion of the shaft 74 to properly align the ports of the valve 90 with the ports of the cylinder 87 is limited by means of a collar 95 which is adapted to be rigidly secured to the shaft 74 by a set screw 94, one end of said collar being recessed, as indicated at 96 in Fig. 17, for the reception of a lateral projection 97, in the present instance, formed on the bearing 75, the width of the recess 96 being slightly larger than the width of the projection 97 to permit just sufficient rocking motion of the shaft 74 to align the ports of the valve 90 with the ports of the cylinder 87 respectively at the extreme limits of the rocking motion of the shaft 74.

If desired, the segment 57 may be operated directly from the shaft 74 and for this purpose the collar 95 is provided with a projection 98 which is adapted to fit tightly within the notch or recess 99 formed in the one end of the hub 73, in which case the set screw 94 is released and the collar 95 moved longitudinally along the shaft 74, releasing the recess 96 thereof from the projection 97 on the bearing 75 and bringing the projection 98 on the opposite end of said collar 95 into the recess 99 of the hub 73, as clearly illustrated in Fig. 18, whereupon the set screw 94 is again tightened, thereby clamping the hub 73 rigidly to the shaft 74. In such case the link 84 which connects the lever 83 with the piston rod 85 is disconnected from the said lever 83; and the link 89, which connects the lever 88 with the valve 90, is likewise disconnected from the lever 88, consequently rocking motion of the shaft 74 by the foot treadle 92 is transmitted directly to and through the shaft 74 and through the links 68 and 66 to the segment 57.

Figs. 21 to 25 inclusive illustrate a modified form of operating mechanism between the actuating element 20 and the lever 72, wherein the piston 50 is replaced by a split head 150 in which is confined a ball bearing 153 permitting relative rotation between the head 150 and the rod 119 but preventing relative longitudinal movement between the two.

Secured to the head 1 within the casing 152 is a ring 151 which is secured to the head 1 by screws 149, 149. The ring 151 is provided with a lug 148 having a yoke end 147 supporting a pivot pin 158 on which is pivotally mounted a lever 157. The opposite end of the lever 157 is pivotally connected at 165 to one end of the link 66a, the opposite end of which is pivoted at 67a to the link 68a.

The lever 157 is provided with a roller 169 adapted to bear against the head 150 substantially in axial alignment with the rod 119.

Rocking of the shaft 74 will, through the lever 72 and links 66a and 68a, rock the lever 157 which through the roller 169 bearing against the head 150 will move the rod 119 longitudinally in opposition to the spring 55a, whereby the expansion of the stocking form will be effected.

The expansion of the form in this instance is limited by a cam follower 160 carried by the head 150 and engaging spirally inclined cam surface 162 formed on a ring 161 which is rotatably mounted and confined between the head 1 and ring 151 by and in an annular recess formed 75

in the ring 151. Rotation of the ring 161 will bring the various elevations of the cam surfaces 162 into alignment with the cam followers 160, whereby inward movement of the head 50 toward 5 the head 1 is definitely controlled.

Rotation of the ring 161, to effect adjustment of the cam surface 162 relative to the cam follower 160, and the locking of the cam ring 161 into its adjusted position is effected by a screw 10 163 which is tapped into the cam extension on the ring 161 and projects through a segmental slot 178 formed in casing 152.

Fig. 26 illustrates a detachable interchangeable foot piece 108 which, like the foot piece 8, 15 is composed of two similar parts projecting from the outer ends of the leg shell halves 6a and 6b respectively. Fig. 26 illustrates the one half 108b of the interchangeable foot piece 108 as being connected to the shell half 6b, said shell half 20 being provided with outwardly projecting pins or dowels 109 and 110 fitting within openings 111 and 112 respectively in the end of the foot piece 108b. In the present instance the dowel 109 is notched at 107 for the reception of a spring- 25 pressed ball 106 carried by the foot piece 108b and providing means whereby the foot piece 108b is locked to the shell half 6b, it being understood that the dowels 109 and 110 are shrunk, sweated or otherwise firmly secured in the shell half 6b. 30 As shown in Fig. 12, the filler pieces 18 are each provided with a dovetailed groove for reception of the correspondingly shaped tongues 41 which removably and adjustably connect the 35 foot halves 6a and 6b to the leg halves 6a and 6b respectively, whereby the filler pieces are maintained in position between the leg and foot portions of each of the segmental longitudinally extending sections of the expandible form.

The instep portion of a stocking being inspect- 40 ed on the form, as shown in Fig. 1, is engaged by those portions of the leg shell segments 6a and 6b, respectively, lying immediately adjacent the foot segments 8a and 8b, directly opposite to the slots 46 formed in the leg shell segments 45 through which the heel expander 30 is projected.

The foot piece is provided with an opening 113 50 extending at an angle to the axis of the form from the extreme end 114 of the foot piece to a point immediately adjacent the opposite end 9 of the 55 foot piece, which is used in turning a stocking inside out for inspecting both faces thereof. The welt end of the stocking is run through the opening 113 and spreads radially over the end 114 of the foot piece, whereupon, by grasping the top edge of the welt or open end of the stocking and drawing the stocking up over the form the previous inside surface of the stocking is turned out for inspection.

By providing the rotary mounting for the central post 5 the collapsible form with a stocking thereon may be readily revolved about the axis of the form to facilitate inspection of the entire outer surface of the stocking on the form; and by providing the ball and socket joint between the form-supporting head 1 and the supporting structure 17 the form may be adjusted and clamped at any practically desired angle relative to the table to facilitate the inspections, the universal linkage between the actuating element 20 and the treadle 92 permitting such adjustment of the form without disturbing the connections between the treadle and the form.

By expanding all sections of the form simultaneously and radially the same stretching effect is attained as that attending the pulling of the

stocking onto the leg of the wearer, i. e. all portions of the stocking fabric are stretched correspondingly at the same time and uniformly throughout.

For brevity in the specification and claims, the term "hosiery inspecting device" is employed in a generic sense, wherever the context permits, to define an inspecting device for use with hosiery or other tubular garments or apparel in which defects therein may be discerned in the manner of defects in hosiery; and the term "stocking form" is used to define the form over which the stocking or other article of apparel to be inspected is stretched.

Of course, the hosiery inspecting device specifically shown and described can be changed and modified in various ways without departing from the invention herein disclosed and hereinafter claimed.

We claim:

1. A hosiery inspecting device comprising a hollow stocking form of substantially circular cross-sectional contour composed of a plurality of segmentally surfaced sections respectively extending substantially the full length of the form, 25 a central post disposed within the hollow form, means for operatively connecting said sections to the central post for radial movement respectively relative to the axis thereof, and means carried by the central post for radially moving each 30 of said sections relative to another thereby to expand said stocking form.

2. A hosiery inspecting device comprising a hollow stocking form of substantially circular cross- 35 sectional contour composed of a plurality of segmentally surfaced longitudinally extending sections, a central post disposed within the hollow form, means slidably connecting said sections to the central post for radial movement respectively relative to the axis thereof, and means carried by 40 the central post for radially moving each of said sections relative to another thereby to expand said stocking form.

3. A hosiery inspecting device comprising a hollow stocking form of substantially circular cross- 45 sectional contour composed of a plurality of segmentally surfaced sections respectively extending substantially the full length of the form for engagement with the leg, foot and intermediate instep portions of a stocking, a central post disposed within the hollow form, means for operatively connecting said sections to the central post for radial movement respectively relative to the axis thereof, a heel expander operatively connected to the central post, and means carried by the central post for radially moving each of said sections and said heel expander relative to the axis of the form 50 thereby to expand the stocking form.

4. A hosiery inspecting device comprising a stocking form of substantially circular cross- 60 sectional contour composed of a plurality of segmental surfaces respectively extending substantially the full length of the form for engagement with the leg, foot and intermediate instep portions of a stocking, a heel-engaging surface opposite said instep-engaging surface and normally disposed substantially within the circular contour of the form, and means for radially expanding 65 said surfaces differentially, whereby the heel surface is extended beyond the expanded circular 70 contour of the form.

5. A hosiery inspecting device comprising a stocking form of substantially circular cross- 75 sectional contour composed of a plurality of segmental surfaces respectively extending substan-

tially the full length of the form for engagement with the leg, foot and intermediate instep portions of a stocking, a heel-engaging surface opposite said instep-engaging surface, and means for radially expanding said surfaces differentially, whereby the heel-engaging surface moves at a different rate of speed than the other surfaces.

5 6. A hosiery inspecting device comprising a stocking form of substantially circular cross-sectional contour composed of a plurality of segmental surfaces respectively extending substantially the full length of the form for engagement with the leg, foot and intermediate instep portions of a stocking, a heel-engaging surface opposite said instep-engaging surface, and means for radially expanding said leg and foot surfaces and said heel surface differentially to expand the leg surfaces in excess of the expansion of the foot surfaces and to project the heel surface beyond the expanded circular contour of said leg and foot surfaces of the form.

10 7. A hosiery inspecting device comprising a stocking form of substantially circular cross-sectional contour including a tapered leg section and a substantially cylindrical foot section each composed of a plurality of segmental stocking-engaging surfaces, a heel-engaging surface normally disposed substantially within the circular contour of the form adjacent the foot section thereof, and means for radially expanding said surfaces differentially to extend the leg surfaces at one end of the form in excess of the leg and foot surfaces at the opposite end of the form and to extend the heel surface beyond the expanded circular contour of the form.

15 8. A hosiery inspecting device comprising a hollow stocking form of substantially circular cross-sectional contour including a tapered leg section and a substantially cylindrical foot section each composed of a plurality of segmental stocking-engaging surfaces, a heel-engaging surface normally disposed substantially within the circular contour of the form adjacent the foot section thereof; and means confined within the hollow form for radially expanding said surfaces differentially to extend the leg surfaces at one end of the form in excess of the leg and foot surfaces at the opposite end of the form and to extend the heel surface beyond the expanded circular contour of the form.

20 9. A hosiery inspecting device comprising a hollow stocking form of substantially circular cross-sectional contour including a tapered leg section and a substantially cylindrical foot section each composed of a plurality of segmental stocking-engaging surfaces, a heel-engaging surface normally disposed substantially within the circular contour of the form adjacent the foot section thereof, and means confined within the hollow form for radially expanding said surfaces differentially to extend the leg surfaces at one end of the form in excess of the leg and foot surfaces at the opposite end of the form and to extend the heel surface beyond the expanded circular contour of the form, said means comprising a common actuator extending longitudinally of the form and projecting from the larger end of the leg section thereof.

25 10. A hosiery inspecting device comprising a hollow stocking form of substantially circular cross-sectional contour composed of a plurality of segmentally surfaced longitudinally extending sections, a central post disposed within the hollow form, means slidably connecting said sections to the central post for radial movement respectively

relative to the axis thereof, a heel expander pivotally connected to the central post, and means carried by the central post for radially expanding said sections relative to the axis of the form and for swinging said heel expander in a plane radially to the axis of the post.

30 11. A hosiery inspecting device comprising a hollow stocking form of substantially circular cross-sectional contour composed of a plurality of segmentally surfaced longitudinally extending sections, a central post disposed within the hollow form, a supporting lug on each of said sections slidably mounted in a radially extending slot in said post, and means in and extending longitudinally of the post and operatively connected to said lugs for effecting radial movement of the sections.

35 12. A hosiery inspecting device comprising a hollow stocking form of substantially circular cross-sectional contour composed of a plurality of segmentally surfaced longitudinally extending sections, a central post disposed within the hollow form, a supporting rod for each of said sections slidably mounted for radial movement in the post, and means in and extending longitudinally of the post and operatively connected to said rods for effecting radial movement of the sections.

40 13. A hosiery inspecting device comprising a hollow stocking form of substantially circular cross-sectional contour composed of a plurality of segmentally surfaced longitudinally extending sections, a central post disposed within the hollow form, a supporting lug on each of said sections adjacent one end thereof and slidably mounted in a radially extending slot formed in said post, a supporting rod for each of said sections and pivotally connected at its outer end to said section adjacent the second end thereof and slidably mounted in a radially extending bearing in said post, and means in and extending longitudinally of the post and operatively connected to said lugs and said rods for effecting radial movement of the sections.

45 14. A hosiery inspecting device comprising a hollow stocking form of substantially circular cross-sectional contour composed of a plurality of segmentally surfaced longitudinally extending sections, a central post disposed within the hollow form, a supporting lug on each of said sections adjacent one end thereof and slidably mounted in a radially extending slot formed in said post, a supporting rod for each of said sections and pivotally connected at its outer end to said sections adjacent the second end thereof and slidably mounted in a radially extending bearing in said post, an operating element slidably mounted in and extending longitudinally of said post, and cooperating pin and cam slot connections between the lugs and the operating element and between the rods and the operating element for effecting radial movement of the respective sections by longitudinal movement of the operating element.

50 15. A hosiery inspecting device comprising a hollow stocking form of substantially circular cross-sectional contour composed of a plurality of segmentally surfaced longitudinally extending sections, a central post disposed within the hollow form, a supporting lug on each of said sections adjacent one end thereof and slidably mounted in a radially extending slot formed in said post, a supporting rod for each of said sections and pivotally connected at its outer end to said section adjacent the second end thereof and slidably mounted in a radially extending bearing

- in said post, an operating element slidably mounted in and extending longitudinally of said post, a pin on said element projecting into a cam slot in each of said lugs and a pin on each of said rods projecting into a cam slot in said element for radially moving said sections by longitudinal movement of said operating element.
16. A hosiery inspecting device comprising a hollow stocking form of substantially circular cross-sectional contour composed of a plurality of segmentally surfaced longitudinally extending sections, a central post disposed within the hollow form, a supporting lug for each of said sections adjacent one end thereof and slidably mounted in a radially extending slot formed in said post, a supporting rod for each of said sections and pivotally connected at its outer end to said section adjacent the second end thereof and slidably mounted in a radially extending bearing in said post, a heel expander section adjacent one end of the form and pivotally connected to the post for swinging movement in a plane radial to the axis of the post, an operating element slidably mounted in and extending longitudinally of said post, and cooperating pin and cam slot connections between the lugs and the operating element and between the rods and the operating element and between the heel expanding section and the operating element for effecting radial movement of the respective sections by longitudinal movement of the operating element.
17. A hosiery inspecting device comprising a hollow stocking form of substantially circular cross-sectional contour composed of a plurality of segmentally surfaced longitudinally extending sections, a central post disposed within the hollow form, means slidably connecting said sections to the central post for radial movement respectively relative to the axis thereof, a heel expander pivotally connected to the central post for swinging movement in a plane radially to the axis of the post, an operating element slidably mounted in and extending longitudinally of said post, actuating means operatively connecting said sections to said operating element, and a pin carried by said operating element and operating in a slot formed in said heel expander, whereby longitudinal movement of said operating element effects radial movement of said sections and said heel expander.
18. A hosiery inspecting device comprising a hollow stocking form of substantially circular cross-sectional contour and split longitudinally into two similar halves, a central post within the hollow form and extending longitudinally thereof, a pair of lugs formed on said form halves respectively and projecting radially in overlapping relation to each other into a transversely extending slot formed in said post, an operating element slidably mounted in and extending longitudinally of said post, and a pin carried by said operating element and projecting into a pair of oblique slots formed in said lugs respectively at oppositely disposed angles relative to the axis of the operating element, a pin carried by each rod and projecting respectively into oblique slots formed in said operating element and extending at opposite angles to the axis thereof, and a pin on the operating element projecting into a cam slot formed in the heel expander for radially moving each of said form halves and said heel expander relative to the post by relative longitudinal movement between the operating element and the post.
19. A hosiery inspecting device comprising a hollow stocking form of substantially circular cross-sectional contour and split longitudinally into two similar halves, a central post within the hollow form and extending longitudinally thereof, a pair of rods slidably mounted in transversely extending bearings formed in said post and pivotally connected to said form halves respectively and projecting radially in overlapping relation to each other into a transversely extending slot formed in said post, an operating element slidably mounted in and extending longitudinally of said post, and a pin carried by said operating element and projecting into a pair of oblique slots formed in said lugs respectively at oppositely disposed angles relative to the axis of the operating element, for radially moving each of said form halves relative to the post by relative longitudinal movement between the operating element and the post.
20. A hosiery inspecting device comprising a hollow stocking form of substantially circular cross-sectional contour and split longitudinally into two similar halves, a central post within the hollow form and extending longitudinally thereof, a heel expander pivotally mounted on the post for swinging movement in a plane radially disposed to the axis of the post and coincident with the plane of the longitudinal split of said form, an operating element slidably mounted in and extending longitudinally of the post, and a pin on the operating element projecting into a cam slot formed in the heel expander for moving said heel expander radially by relative longitudinal movement between the operating element and the post.
21. A hosiery inspecting device comprising a hollow stocking form of substantially circular cross-sectional contour and split longitudinally into two similar halves, a central post within the hollow form and extending longitudinally thereof, a pair of lugs formed on said form halves respectively and projecting radially in overlapping relation to each other into a transversely extending slot formed in said post, a pair of rods slidably mounted in transversely extending bearings formed in said post and pivotally connected to said form halves respectively, a heel expander pivotally mounted on the post for swinging movement in a plane radially disposed to the axis of the post, an operating element slidably mounted in and extending longitudinally of said post, a pin carried by said operating element and projecting into a pair of oblique slots formed in said lugs respectively at oppositely disposed angles relative to the axis of the operating element, a pin carried by each rod and projecting respectively into oblique slots formed in said operating element and extending at opposite angles to the axis thereof, and a pin on the operating element projecting into a cam slot formed in the heel expander for radially moving each of said form halves and said heel expander relative to the post by relative longitudinal movement between the operating element and the post.
22. A hosiery inspecting device comprising a radially expansible stocking form of substantially circular cross-sectional contour composed of a plurality of segmental longitudinally extending sections each including a leg portion and a foot portion attached to one end of the leg portion and being longitudinally movable relative to said leg portion.
23. A hosiery inspecting device comprising a radially expansible stocking form of substantially circular cross-sectional contour composed of a plurality of segmental longitudinally extending sections each including a leg portion and a foot portion connected to and readily detachable from the leg portion and being longitudinally extensible relative to said leg portion.
24. A hosiery inspecting device comprising a radially expansible stocking form of substantially circular cross-sectional contour composed of a plurality of segmental longitudinally extending sections each including a leg portion and a rela-

tively longitudinally extensible foot portion secured to the leg portion, and substantially circularly contoured filler pieces insertable between the leg and foot portions of the form for radial 5 expansion therewith.

25. A hosiery inspecting device comprising a radially expansible stocking form of substantially circular cross-sectional contour composed of a plurality of segmental longitudinally extending 10 sections each including a leg portion and a relatively longitudinally extensible foot portion, a tongue extending from one of said portions of each section into the other of said portions thereof longitudinally of the form, and means for securing the tongues in their adjusted positions in 15 the form sections respectively.

26. A hosiery inspecting device comprising a radially expansible stocking form of substantially circular cross-sectional contour composed of a plurality of segmental longitudinally extending 20 sections each including a leg portion and a relatively longitudinally extensible foot portion, a tongue extending from one of said portions of each section into the other of said portions thereof 25 longitudinally of the form, a substantially circularly contoured filler piece carried by each tongue between the leg and foot portions of each section of the form, and means for securing the tongues in their adjusted positions in the form 30 sections respectively.

27. A hosiery inspecting device comprising a radially expansible stocking form of substantially circular cross-sectional contour composed of a plurality of segmental longitudinally extending 35 sections each including a leg portion and a relatively longitudinally extensible foot portion, and a tongue of dovetailed cross-section secured in and extending longitudinally from the foot portion of each section into a correspondingly shaped 40 groove formed in the leg portion of the section for adjustably connecting said portions.

28. A hosiery inspecting device comprising a radially expansible stocking form of substantially circular cross-sectional contour composed of a plurality of segmental longitudinally extending 45 sections each including a leg portion and a relatively longitudinally extensible foot portion, a tongue of dovetailed cross-section secured in and extending longitudinally from the foot portion 50 of each section into a correspondingly shaped groove formed in the leg portion of the section and provided with a longitudinally extending locking groove, and means carried by the leg portion and projecting into said locking groove for 55 securing the tongue in its adjusted position in said leg portion.

29. A hosiery inspecting device comprising a radially expansible stocking form of substantially circular cross-sectional contour composed of a plurality of segmental longitudinally extending 60 sections each including a leg portion and a relatively longitudinally extensible foot portion, a tongue of dovetailed cross-section secured in and extending longitudinally from the foot portion of each section into a correspondingly shaped groove 65 formed in the leg portion of the section and provided with a longitudinally extending locking groove, a screw carried by the leg portion and provided with a flange projecting into said locking 70 groove for securing the tongue in its adjusted position in said leg portion.

30. A hosiery inspecting device comprising a radially expansible stocking form of substantially circular cross-sectional contour composed of 75 a plurality of segmental longitudinally extending

sections each including a leg portion and a relatively longitudinally extensible foot portion, a tongue of dovetailed cross-section secured in and extending longitudinally from the foot portion of each section into a correspondingly shaped groove 5 formed in the leg portion of the section for adjustably connecting said portions, and a filler piece between the leg and foot portions of each section and provided with a dovetailed groove 10 embracing the tongue for securing said filler piece in said position relative to the foot and leg portions of the form section.

31. A hosiery inspecting device comprising a radially expansible stocking form of substantially circular cross-sectional contour composed of 15 a plurality of segmental longitudinally extending sections each including a leg portion and a relatively longitudinally movable foot portion attached to one end of the leg portion, a dowel secured in one of said portions and projecting 20 into an opening formed in the other of said portions, and a resilient element adjacent and projecting into said opening for engagement with the dowel to secure said portions together.

32. A hosiery inspecting device comprising a 25 stocking form of substantially circular cross-sectional contour, a heel piece normally disposed within the circular contour of the form and adapted to be projected laterally therebeyond through a slot provided in one side of the form, 30 said heel piece comprising a supporting section pivotally mounted within the form, and a body section secured to the supporting section for adjustment relative thereto longitudinally of the 35 form.

33. A hosiery inspecting device comprising a stocking form of substantially circular cross-sectional contour, a heel piece normally disposed within the circular contour of the form and adapted to be projected laterally therebeyond 40 through a slot provided in one side of the form, said heel piece comprising a pair of laterally spaced plates pivotally mounted within the form, a body section provided with a longitudinally 45 extending rib disposed between said plates, and means for securing said plates to said rib to permit relative adjustment therebetween longitudinally of the form.

34. A hosiery inspecting device comprising a 50 stocking form of substantially circular cross-sectional contour, a heel piece normally disposed within the circular contour of the form and adapted to be projected laterally therebeyond through a slot provided in one side of the form, 55 said heel piece comprising a pair of laterally spaced plates pivotally mounted within the form, a body section provided with a longitudinally extending rib disposed between said plates, means for securing said plates to said rib to permit relative adjustment therebetween longitudinally of 60 the form, an operating element for said heel piece extending longitudinally through said form, and a pin extending laterally from opposite sides of said operating element into cam slots respectively formed in said plates for swinging said heel piece 65 radially of the form by longitudinal movement of said operating element.

35. Hosiery inspecting apparatus comprising, in combination, a stocking form having a plurality of expansible segments, means within said 70 stocking form for expanding said segments; mounting means rotatably supporting the stocking form, comprising a housing having therein a movement translating device comprising rack and gear members for operating said expanding 75

means; a separably mounted fluid operated power device comprising a movement imparting member, valve means for controlling said power device; means operable at will for controlling said 5 valve means; and movement transmitting means connecting said movement imparting member with said rack and gear members.

36. A hosiery inspecting device comprising a supporting structure including a head, a stud 10 projecting from one side of said head, a post rotatably mounted on said stud, an expansible stocking form carried by said post, a rod extending axially of the stud and post and beyond the opposite side of said head for actuating said form, 15 a treadle carried by the supporting structure, means operatively connecting the treadle and said rod, including a fluid operated cylinder having a piston operatively connected to the rod, and a fluid control valve operatively connected to the 20 treadle.

37. A hosiery inspecting device comprising a supporting structure including a head, a stud projecting from one side of said head, a post rotatably mounted on said stud, an expansible 25 stocking form carried by said post, a rod extending axially of the stud and post and beyond the opposite side of said head for actuating said form, a treadle carried by the supporting structure, a fluid operated cylinder rigidly secured to the supporting structure, a piston in said cylinder operatively connected to the rod, a fluid control valve for said cylinder, and means operatively connecting said treadle and said valve.

38. A hosiery inspecting device comprising a 35 supporting structure, a head, means for securing said head to said structure and providing for universal angular adjustment of the head relative to the supporting structure, a stud projecting from one side of said head, a post rotatably 40 mounted on said stud, an expansible stocking form carried by said post, a rod extending axially of the stud and post and beyond the opposite side of said head for actuating said form, a fluid actuated cylinder secured to said supporting structure, a piston in the cylinder, universal linkage 45 operatively connecting the piston to said rod, and a fluid control valve for controlling the actuation of the piston.

39. A hosiery inspecting device comprising a 50 supporting structure, a head, means for securing said head to said structure and providing for universal angular adjustment of the head relative to the supporting structure, a stud projecting from one side of said head, a post rotatably 55 mounted on said stud, an expansible stocking form carried by said post, a rod extending axially of the stud and post and beyond the opposite side of said head for actuating said form, a fluid actuated cylinder secured to said supporting structure, a piston in the cylinder, universal linkage 60 operatively connecting the piston to said rod, a fluid control valve for controlling the actuation of the piston, and a treadle carried by the supporting structure and operatively connected to said valve.

40. A hosiery inspecting device comprising a supporting structure, a head, means for securing said head to said structure and providing for universal angular adjustment of the head relative 70 to the supporting structure, a stud projecting from one side of said head, a post rotatably mounted on said stud, an expansible stocking form carried by said post, a rod extending axially of the stud and post and beyond the opposite side 75 of said head for actuating said form, a shaft ro-

tatably carried by the supporting structure, a treadle carried by the shaft, a fluid actuated cylinder secured to said supporting structure, a piston in the cylinder, universal linkage operatively connecting the piston to said rod, including a lever loosely mounted on said shaft, a lever secured tightly to said shaft, and a fluid control valve operatively connected to said tight lever. 5

41. A hosiery inspecting device comprising a supporting structure, a head, means for securing 10 said head to said structure and providing for universal angular adjustment of the head relative to the supporting structure, a stud projecting from one side of said head, a post rotatably mounted on said stud, an expansible stocking 15 form carried by said post, a rod extending axially of the stud and post and beyond the opposite side of said head for actuating said form, a shaft rotatably carried by the supporting structure, a treadle carried by the shaft, a fluid actuated cylinder 20 secured to said supporting structure, a piston in the cylinder, universal linkage operatively connecting the piston to said rod, including a lever loosely mounted on said shaft, a lever secured tightly to said shaft, a fluid control valve 25 operatively connected to said tight lever, and a collar mounted on said shaft for movement axially thereof into interlocking engagement with said loose lever to lock the loose lever to the shaft for directly operating said rod from said shaft, 30 and means for disconnecting the piston and the valve from said loose and tight levers respectively.

42. A hosiery inspecting device comprising a supporting structure, a head, means for securing 35 said head to said structure and providing for universal angular adjustment of the head relative to the supporting structure, a stud projecting from one side of said head, a post rotatably mounted on said stud, an expansible stocking 40 form carried by said post, a rod extending axially of the stud and post and beyond the opposite side of said head for actuating said form, a cylinder carried by said head at the said opposite side thereof and into which the end of said rod extends, a piston on the said end of said rod, a gear 45 rack on one side of the piston and projecting through a slot formed in one side of the cylinder, a gear segment pivotally mounted on the head adjacent the slot in the cylinder and intermeshing with said gear rack, a treadle pivotally 50 mounted on said supporting structure, and means including universal linkage operatively connecting the treadle and the gear segment for actuating the rod.

43. A hosiery inspecting device comprising a 55 supporting structure, a head, means for securing said head to said structure and providing for universal angular adjustment of the head relative to the supporting structure, a stud projecting from one side of said head, a post rotatably 60 mounted on said stud, an expansible stocking form carried by said post, a rod extending axially of the stud and post and beyond the opposite side of said head for actuating said form, a spring tending to move the rod in one direction to collapse the form, means for moving the rod in an opposite direction to expand the form including a treadle pivoted to the supporting structure, and universal linkage operatively connected to the treadle and including a lever pivoted to the head 65 adjacent the projecting end of the rod and provided with a projection adapted to press the rod axially in opposition to the spring. 70

44. A hosiery inspecting device comprising a supporting structure, a head, means for securing 75

said head to said structure and providing for universal angular adjustment of the head relative to the supporting structure, a stud projecting from one side of said head, a post rotatably mounted on said stud, an expansible stocking form carried by said post, a rod extending axially of the stud and post and beyond the opposite side of said head for actuating said form, a spring tending to move the rod in one direction to collapse the form, means for moving the rod in an opposite direction to expand the form including a treadle pivoted to the supporting structure, universal linkage operatively connected to the treadle and including a lever pivoted to the head adjacent the projecting end of the rod and provided with a projection adapted to press the rod axially in opposition to the spring, and means for adjustably controlling the form expanding movement of the rod.

45. A hosiery inspecting device comprising a supporting structure, a head, means for securing said head to said structure and providing for universal angular adjustment of the head relative to the supporting structure, a stud projecting from one side of said head, a post rotatably mounted on said stud, an expansible stocking form carried by said post, a rod extending axially of the stud and post and beyond the opposite side of said head for actuating said form, a spring tending to move the rod in one direction to collapse the form, means for moving the rod in an opposite direction to expand the form including a treadle pivoted to the supporting structure, universal linkage operatively connected to the treadle and including a lever pivoted to the head adjacent the projecting end of the rod and provided with a projection adapted to press the rod axially in opposition to the spring, means for adjustably controlling the form expanding movement of the rod, comprising a head on the said projecting end of the rod, an adjustable cam surface carried by one of said heads, and a cam follower carried by the other of said heads and engaging the cam surface.

46. A hosiery inspecting device comprising a supporting structure, a head, means for securing said head to said structure and providing for universal angular adjustment of the head relative to the supporting structure, a stud projecting from one side of said head, a post rotatably mounted on said stud, an expansible stocking form carried by said post, a rod extending axially of the stud and post and beyond the opposite side of said head for actuating said form, a cylinder carried by said head at the said opposite side thereof and into which the end of said rod extends, a piston on the said end of said rod, a gear rack on one side of the piston and projecting

through a slot formed in one side of the cylinder, a gear segment pivotally mounted on the head adjacent the slot in the cylinder and intermeshing with said gear rack, a treadle pivotally mounted on said supporting structure, means including universal linkage operatively connecting the treadle and the gear segment for actuating the rod in one direction to expand the form, an extension on said piston projecting beyond the end of the cylinder, and a collar adjustably mounted on said piston extension for engagement with the end of the cylinder to limit the form expanding motion of the rod.

47. A hosiery inspecting device comprising a supporting structure, a head, means for securing said head to said structure and providing for universal angular adjustment of the head relative to the supporting structure, a stud projecting from one side of said head, a post rotatably mounted on said stud, an expansible stocking form carried by said post, a rod extending axially of the stud and post and beyond the opposite side of said head for actuating said form, a cylinder carried by said head at the said opposite side thereof and into which the end of said rod extends, a piston on the said end of said rod, a gear rack on one side of the piston and projecting through a slot formed in one side of the cylinder, a gear segment pivotally mounted on the head adjacent the slot in the cylinder and intermeshing with said gear rack, a treadle pivotally mounted on said supporting structure, means including universal linkage operatively connecting the treadle and the gear segment for actuating the rod in one direction to expand the form, an extension on said piston projecting beyond the end of the cylinder, a collar adjustably mounted on said piston extension for engagement with the end of the cylinder to limit the form expanding motion of the rod, and a spring for moving said rod in a form contracting direction.

48. A hosiery inspecting device comprising an expansible stocking form of circular cross-sectional contour split longitudinally into two similar halves each including a leg portion and a foot portion attached to one end of the leg portion, said foot portion having a stocking turning opening extending from the outer end of the foot portion to a point adjacent that end of the leg portion to which said foot portion is attached, said opening being formed correspondingly in each of the halves of said foot portion with its axis at an angle to the axis of the form in a plane coincident with the plane of the longitudinal split of the form.
